United States Patent Office.

THOMAS S. CLOGSTON, OF BOSTON, MASSACHUSETTS.

Letters Patent No. 65,874, dated June 18, 1867.

IMPROVEMENT IN STEAM GENERATORS.

The Schedule referred to in these Letters Patent and making part of the same.

TO ALL PERSONS TO WHOM THESE PRESENTS SHALL COME:

Be it known that I, THOMAS S. CLOGSTON, of Boston, in the county of Suffolk, and State of Massachusetts, have invented a new and useful Improvement in Steam Boilers; and do hereby declare the following to be a full, clear, and exact description thereof, due reference being had to the accompanying drawings, making part of this specification, and in which—

Figure 1 is a side elevation.

Figure 2, a front end elevation.

Figure 3, a vertical and longitudinal section; and

Figure 4, a transverse section of a steam boiler constructed in accordance with my invention.

Figure 5 being a front view of one of the generators.

The invention in question is an improvement in that class of steam boilers known as cast-iron sectional boilers, or those in which a series of tubular sections, in any requisite number, are riveted together to form a whole, and which are enclosed in a suitable chamber of brick-work.

The invention consists in the peculiar construction, as well as the mode of union of the sections, as hereinafter described.

By referring to the drawings above mentioned as illustrating my invention, the boiler will be seen as consisting of a series of sections or generators, A A, etc., cast in one homogeneous piece of iron, and composed of a number of upright pipes or flues, E E, etc., of different lengths, the upper ends of which open into two steam chambers, L L, the lower ends of these pipes being joined by and opening into a semicircular or arched pipe or flue, N, the different pipes being in open communication with each other, and forming steam and water circulating chambers. The lower terminations of the arched flue N and those of the outer upright flues E E unite to form what I term the water-legs E' E', the space enclosed between these legs and below the arch being the fuel combustion-chamber of the furnace. Each generator is formed on each side with five or any other suitable number of offsets, F F F, etc., a port, I, being formed in each offset to open communication between the interior of the different sections. Each generator A is also formed with offsets H H, surrounding the steam chambers L L, which are in a vertical plane with the offsets F F before mentioned. An annular groove, a, is formed in the face of each of these offsets F H, etc., and surrounding the posts, as shown in fig. 3 of the drawings, and in such manner that when the two generators are bolted together, these grooves shall come in alignment, a suitable composition packing having previously been placed in them, which seals the joint, and prevents leakage from the generator. Any suitable number of the above-described sections, according to the required capacity of the boiler, are to be securely bolted together, and placed within a suitable chamber of brick-work, the outermost section forming the front end of the boiler. A rectangular tubular casing, B, is applied to this intersection by means of offsets and posts, formed upon it to correspond with those of the section, the fuel-supply door S being applied to this casing, as represented in the drawings. Furthermore, each generator A has a flue, C, communicating with the steam-chambers L L to extend upward into a common conduit or reservoir. A horizontal foraminous plate or partition, b, is extended across the steam-chambers L L, as shown in fig. 4, the combined area of the perforations of the plates, being equal to that of the discharge-flue C, or of just sufficient capacity to carry off the steam generated by the flues below them, the object of these foraminous plates being to divide the body of steam into small jets, and prevent its taking up the quantity of water with it, which is unavoidable in the employment of one large flue, thus enabling me to economize the consumption of water, and to take off "dry steam," as it is termed by engineers. By the application of the tubular chamber B, which connects the water-legs E' E', I am enabled to empty the entire combined boiler of its contents of water. By its employment I also gain a radiating surface, and utilize much heat which has heretofore been lost. It also serves to reduce the temperature of the parts about the fuel-supply door, and which has been the first to be destroyed. The bolts for securing the different sections together pass longitudinally through either or any of the ports I L, the heads of the bolts overlapping the exterior of the casing. By the above-described construction of the sections A A, I obtain a large and rapidly radiating surface for generating steam, as well as excellent circulation throughout the section.

I claim a boiler or steam generator composed of one or more generators A, in which the upright or circulating flues, steam-chamber or chambers, and lower or arched flue are arranged substantially in the manner herein specified.

I also claim the combination with the boiler or steam generator of the tubular casing surrounding the fuel supply door, substantially as and for the purposes set forth.

THOMAS S. CLOGSTON.
